UNITED STATES PATENT OFFICE.

WILLIAM H. GRINDLEY, OF CONGLETON, ENGLAND, ASSIGNOR TO WILLIAM S. PITCAIRN, OF NEW YORK, N. Y.

DESIGN FOR A DISH.

SPECIFICATION forming part of Design No. 27,744, dated October 19, 1897.

Application filed September 8, 1897. Serial No. 650,996. Term of patent 3½ years.

To all whom it may concern:

Be it known that I, WILLIAM H. GRINDLEY, a citizen of Great Britain, residing at Congleton, Cheshire, England, have invented a certain new and original Design for a Dish; and I do hereby declare the following to be a full, clear, and exact description of the same, reference being had to the accompanying drawings, forming a part hereof.

10 In the drawings, Figure 1 is a top plan view of a dish embodying my design, and Fig. 2 is a central vertical section thereof.

15 The following are the leading features of my design: The dish is essentially circular in shape and consists of a depressed center *a* and a rim *b*, the latter being composed of a surface curved concavely outward. The rim consists of a plurality of sectors or panels repeated around the dish and precisely similar in 20 shape and ornamentation. One of these panels *c* I have set off in the drawings by dotted

lines. It is ornamented at its outer edge with a band which consists of a short convex curve *d*, reversed on each side into two concave curves *d''* and *d'''* and being continued reversed again into two larger convex curves *d'''* and *d''''*. Within this band and parallel thereto are arranged a series of convex scallops *e*, which extend completely around the dish, except that they are interrupted back of the convex curve *d* by an ornamentation *f*, consisting of two scrolls tangent to each other.

What I claim as new is—

35 The design for a dish substantially as shown and described.

In testimony whereof I have signed this specification in the presence of two subscribing witnesses.

WILLIAM H. GRINDLEY.
